UNITED STATES PATENT OFFICE.

ALBERT C. KALK, OF CHICAGO, ILLINOIS, ASSIGNOR TO INVINCIBLE LAUNDRY EQUIPMENT CO., A CORPORATION OF ILLINOIS.

SAFETY DEVICE FOR DRIERS.

Application filed August 23, 1926. Serial No. 131,019.

This invention relates to a safety device for driers.

In driers for clothes and the like, or any driers that involve a rotating cylinder, there is usually a door on the cylinder whereby access is afforded to the interior. These cylinders are usually rotated by a motor and when the drying is completed and the machine is stopped, the door of the cylinder may be at the bottom or at some inconvenient point. Such machines are usually provided with a hand operated pinion which is normally out of mesh with the driving gear but which may be shifted into mesh therewith for operating the same after the motor has stopped for bringing the door on the cylinder into the proper position, for an attendant to unload the cylinder. There is more or less danger involved in having someone tamper with the hand operated pinion and shifting the same into operative position while the drier is running, whereby the rapidly rotating crank handle on the pinion may cause injury to some one, especially the one who is doing the tampering.

It is an object of this invention to eliminate this danger, in the provision of a connection between the hand operated pinion and motor switch whereby the pinion cannot be shifted while the motor is running; that is, when the motor switch is in closed position.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is a fragmentary elevational view of the driving mechanism of a drying machine.

Figure 2 is an enlarged plan view with parts in section taken substantially upon the line II—II of Figure 1.

Figure 3 is an enlarged sectional view taken substantially upon the line III—III of Figure 2 with the shaft 18 omitted.

Figure 4 is an enlarged sectional view taken substantially upon the line IV—IV of

Figure 2 with the parts shifted to normal operative position.

Figure 5 is an enlarged fragmentary side elevational view of the switch box.

Figure 6 is an enlarged plan view of the bifurcated plate 17, of Figure 2.

In the drawing, there is shown a driving or power shaft 1 which is adapted to be driven by a belt 2 and pulley. A pinion 3 is secured upon the end of the shaft 1 and drives a gear 4 which is fixed upon one end of the cylinder supporting shaft 5. The belt 2 is adapted to be connected to a motor 6 (not shown) and together with the gears 3 and 4, constitute the power drive for the cylinder. The manual drive for the cylinder comprises a pinion 6 secured upon a slidably mounted shaft 7 having a crank 8 thereon by which it may be manually rotated. The shaft 7 is slidably mounted in a bearing 9 in the frame 9a of the machine. The pinion 6 is normally out of mesh with the gear 4 and is positioned between such gear and the bearing 9. When the motor has stopped and it is desired to manually rotate the cylinder, the pinion 6 is pulled outwardly. The mechanism so far described and the drier associated therewith are shown in the Butzbach Patent No. 1,549,744, to which reference may be had.

This invention concerns itself with means for preventing the pinion 6 from being shifted into mesh with the gear 4 until the motor circuit has been opened. To this end, the motor switch 10 is attached by a suitable bracket 11 to the side of the frame 9a of the machine and adjacent the inner end of the shaft 7. This switch is illustrated as of the push button type in which the push buttons are indicated by the references 12 and 13.

The inner corners of the switch box are provided with under-cut bearings or sockets 14 for receiving the trunnions 15 on the arms 16 of a bifurcated plate 17, the bifurcation of which receives the push button 13 as shown in Figure 2, and the solid portion of which is provided with a narrow neck or projection 17a which extends over the push button 12, as shown in Figures 2 and 4. A shaft 18 is journalled in the sides of the switch box above the plate 17. The portion of the shaft 18 directly over the plate 17 has a flat por-

tion 19 in contact with such plate when the push button 12 is in elevated position. A handle 20 is secured upon the shaft 18 and this handle is provided with stop lugs 21 for limiting the swinging movement thereof. These stop lugs are adapted to engage a suitable casting 22 on the switch box. The bifurcated arms of the plate 17 are provided with rising lugs 23 which extend above the shaft 18 and which consequently maintains the plate 17 in position.

An angle member 24 is secured upon the end of the shaft 7. It will be noted that the vertical portion thereof is rigidly attached 15 to the shaft while the horizontal portion extends over the switch box and over the neck 17^a of the plate 17. This horizontal portion is provided with a notch or cut out portion 25 (Figure 2) which is similar to the neck 20 17^a on the plate 17 and is of such a size that the said neck 17^a may pass therethrough.

It will be understood that the electric motor that operates the drier will be connected to the switch 10 and that the switch button 25 13 must be depressed to start the motor. As the push button 13 is depressed, the push button 12 will rise. When the pinion 6 is located in its inoperative position between the gear 4 and the frame of the machine, the cut out 30 portion 25 will be directly over the neck 17^a on plate 17 and the motor may be started by depressing the button 13, the button 12 rising and elevating the neck 17^a into the cut out portion 25 of the angle member 24, as 35 shown in Figure 4. With the neck 17^a in such cut out portion, the plate 17 will act as a stop and prevent any one from shifting the pinion 6 into mesh with gear 4 while the motor is running.

40 When the motor has been stopped by swinging the handle 20 to the dotted line position shown in Figure 4, and thereby depressing the neck 17^a of plate 17 below the cut out portion 25, the angle member 24 will be released from its interlocking engagement with the plate 17 and the pinion 6 may be shifted into mesh with gear 6. This position is shown in Figures 1 and 2, and it will be noted that the horizontal portion of the angle 24 has 45 been moved so that it extends over the neck 17^a of the plate 17 and prevents the switch from being operated as long as the pinion 6 is in mesh with the gear 4. Before the motor can be again started, it will be necessary 50 to shift the pinion 6 to its inoperative position to bring the notch 25 over the neck 17^a of plate 17.

From the foregoing, it will be apparent that a very simple safety device has been 60 provided that prevents the manual operation of the machine as long as the power drive is operating, and that on the other hand, prevents the power drive from being applied as long as the manual drive is effective.

65 I am aware that many changes may be

made, and numerous details of construction may be varied through a wide range without departing from the principles of this invention, and I therefore do not purpose limiting the patent granted hereon, otherwise than necessitated by the prior art.

I claim as my invention:

1. In a machine of the class described, a power driving circuit embodying a switch, an auxiliary manual drive for the machine, 75 said manual drive having means interlocking with said switch when the latter is in closed position.

2. In a machine of the class described, a power driving circuit including a switch, an auxiliary manual drive for the machine having an operative and an inoperative position, and a device on said manual drive for locking said switch in open position when said 80 drive is in its operative position.

3. In a machine of the class described, a power driving circuit including a switch, an auxiliary manual drive for the machine having an operative and an inoperative position, and means on said manual drive adapted for 90 interlocking engagement with said switch when said drive is in inoperative position and the switch is in closed position, said means locking said switch against operation when said switch is in open position and said drive is in operative position.

4. In a machine of the class described, a power circuit including a switch, a manual drive having a member extending over said switch and having an operative and an inoperative position, said switch being operable when said manual drive is in inoperative position and inoperative when said drive is 100 in operative position.

5. In a machine of the class described, a power circuit including a switch, a manual drive having an operative and an inoperative position, and a device extending over said switch, and means operable by said switch when said drive is in its inoperative position 105 for interlocking with said device.

6. In a machine of the class described, a power circuit including a switch, a drive for the machine having an operative and an inoperative position and a member extending over said switch, means operated by said switch when said drive is in inoperative position for interlocking with said member, said member preventing operation of said switch when said drive is in operative position.

7. In a machine of the class described, a power circuit including a switch, a manual drive having an operative and inoperative position, and a member extending over said switch and having a notch, a locking member actuated by the closing of said switch for interlocking engagement with said notch when said drive is in inoperative position, and means for depressing said locking member and simultaneously opening said switch, said 125

first mentioned member preventing the operation of said switch when said drive is in operative position.

8. In a machine of the class described, a power circuit including a push button switch, a manual drive having an operative and an inoperative position, and a notched plate extending over said switch, a pivoted device extending over one button of the switch and adapted to be operated by the closing of said switch for engaging said notch when said drive is in inoperative position, means for depressing said device and simultaneously opening said switch, means for shifting said

15 drive to operative position and simultane-

ously moving said plate over said pivoted member for preventing the closing of said switch.

9. In a machine of the class described, a power circuit including a switch, an auxiliary 20 manual drive having an operative and an inoperative position, means for locking said drive in its inoperative position when said switch is closed, means for unlocking said drive when the switch is opened, and means 25 for preventing the operation of said switch when said drive is in operative position.

In testimony whereof I have hereunto subscribed my name.

ALBERT C. KALK.
